UNITED STATES PATENT OFFICE

HYMAN CHARNIN, OF NEW YORK, N. Y.

DESIGN FOR A BOOTH FOR RESTAURANTS

Application filed August 27, 1931. Serial No. 40,941. Term of patent 14 years.

To all whom it may concern:

Be it known that I, HYMAN CHARNIN, a citizen of the United States, residing at New York, in the county of Bronx and State of New York, have invented a new, original, and ornamental Design for Booth for Restaurants, of which the following is a specification, reference being had to the accompanying drawing, forming part therof.

The figure is a perspective view of the booth showing the side walls as well as the front of the rear wall of the booth, the rear of the rear wall of the booth being either plain or the same as the front of said wall.

I claim:

The ornamental design for a booth for restaurants, as shown and described.

HYMAN CHARNIN.
